UNITED STATES PATENT OFFICE.

GEORGE E. DARLING, OF PROVIDENCE, RHODE ISLAND.

DESIGN FOR A BADGE-PIN.

SPECIFICATION forming part of **Design No. 27,420**, dated **July 27, 1897**.

Application filed March 17, 1897. Serial No. 628,052. Term of patent 7 years.

To all whom it may concern:

Be it known that I, GEORGE E. DARLING, a citizen of the United States, residing at Providence, in the State of Rhode Island, have 5 invented and produced a new and original Design for a Badge-Pin, of which the following is a specification, reference being had to the accompanying drawings, forming a part thereof.

10 In the accompanying drawings, Figure 1 represents the front view of a badge-pin embodying my improved design. Fig. 2 represents an edge view of the same.

The leading feature of my design consists 15 in the raised and perforated representation of a bicycle-wheel surmounted by the upper portion of a shield.

In the drawings, A represents the upper portion of a shield, and B the bicycle-wheel, having the spokes C C, with open spaces D D 20 between them. I have also shown the wings E E E arranged in triangular form within the rim of the wheel. The shield A is provided with the field of stars a, the panel b, which may contain any suitable letters and words, 25 the contrasting bars c c', and the sprigs of leaves d d at opposite edges of the shield.

What I claim is—

The design for a badge-pin, herein shown and described:

GEORGE E. DARLING.
